United States Patent Office

Des. 179,197
Patented Nov. 13, 1956

179,197

COFFEE MAKER OR SIMILAR ARTICLE

Bernard A. Graham, Hinsdale, Ill., assignor to Sunbeam Corporation, Chicago, Ill., a corporation of Illinois

Application June 24, 1955, Serial No. 36,668

Term of patent 14 years

(Cl. D44—26)

Fig. 1 is a side elevational view of a coffee maker or similar article showing my new design;

Fig. 2 is a front elevational view thereof;

Fig. 3 is a side elevational view, from the opposite side of Fig. 1;

Fig. 4 is a rear elevational view; and

Fig. 5 is a top plan view.

I claim:

The ornamental design for a coffee maker or similar article, substantially as shown.
